RECOVERING GREEN ACID SOAP

Robert E. Beard and Edward N. Roberts, Casper,
Wyo., assignors to Standard Oil Company, Chi-
cago, Ill., a corporation of Indiana

Application June 14, 1932, Serial No. 617,128

2 Claims. (Cl. 87—16)

This invention relates to the recovery of green acid soaps which have been used for treating emulsions in oil refineries or oil fields, and particularly for treating heavy lubricating oils after 5 sulfuric acid refining. Green acid soaps are sodium salts of sulfonic acids of low molecular weight, they are preferentially water soluble, and they may be prepared as described in Humphreys Patent No. 1,474,933, issued November 20, 1923. 10 These green acid soaps are usually produced in the manufacture of highly purified oils, such as white oils and medicinal oils, because the sludge from the treatment of ordinary lubricating oils contains too many undesirable impurities.

15 Green acid soaps are particularly useful in a number of fields, one of which is the treatment of petroleum oil emulsions. These soaps may be used to break emulsions in accordance with U. S. patent to Rogers No. 1,299,385, issued April 1, 20 1919, to break sludge emulsions as taught by Diggs, U. S. 1,418,781, issued June 6, 1922, or they may be used for extracting mahogany soaps and 25 other desirable impurities from lubricating oils as taught by Bransky No. 1,396,399, issued No- vember 8, 1921.

After using the aqueous green acid soap solution to treat an acid-treated oil, the soap is unfit for further use. The object of our invention is 30 to recover the green acid soap which has been used for washing acid treated oils or breaking emulsions, and to render them fit for reuse by removing undesirable components therefrom.

We have discovered that certain light hydro- 35 carbon oils are remarkably effective for extract- ing undesirable constituents from green acid soaps when the acidity of the mixture is main- tained within predetermined limits. The inven- 40 tion will be more clearly understood from the fol- lowing description, taken in connection with the accompanying drawings which form a part of this specification and in which—

Figure 1 is a flow diagram indicating the general sequence of steps;

Figure 2 is a chart showing the effect of acid- 45 ity of the soap solution upon the separation of oil from the washed soap solution; and

Figure 3 shows the effect of acidity on the ex- traction of impurities from green acid soap solu- 50 tion.

In refining lubricating oils the oil is usually 55 treated with concentrated sulfuric acid. The treatment sulfonates a portion of the oil, or cer- tain constituents thereof, and forms (among other things) sulfonic acids of high molecular weight having pronounced emulsifying proper-

ties and seriously interfering with subsequent neutralization of the treated oil. Furthermore, the acids are converted into soaps which are preferentially oil soluble and which remain in the oil to contaminate the finished product. A highly effective method for removing these undesirable sulfonic acids and mahogany acids from lubricating oils is to mix the neutral oil with an aqueous solution of green acid soap. This aqueous solution exerts a peculiar solvent effect on 10 the mahogany soaps, removing them from solution in the oil.

We have found that the resulting solution of 15 green acid soap, mahogany soap and impurities may be acidified and extracted with a light petro- leum oil. By properly proportioning the oil and regulating the acidity it is possible to remove the 20 impurities from the green acid soap so that it may be used again for treating additional lubri- cating oil.

To cite a specific example, a treated motor base 25 stock distillate from Salt Creek crude having a viscosity of 83 sec. Saybolt at 210° F. is neutralized with caustic soda solution. The mahogany soaps are all extracted by means of about 12½% by volume of a 10% aqueous solution of green 30 acid soap. This spent soap, together with the extracted impurities, is then acidified with 92.5% sulfuric acid until the resulting acidity is about .07-.08 cc. in excess per hundred cc. of soap. About 25% by volume of spindle oil is then mixed 35 with the acidified soap solution and the aqueous phase is separated from the oil phase. The re- vivified soap in the aqueous phase is then added to additional amounts of the sour, treated mo- 40 tor base stock along with the soda which is used for neutralization. The mixing may be effected by blowing in the usual way with air, after which the mixture is allowed to stand at about 190° F. for several hours. The aqueous green acid soap 45 solution carries down the mahogany soap as before.

Green acid soap separates from the spindle oil in a very satisfactory manner and the used soap 50 is practically as efficient as the unused green acid soap in extracting the mahogany compounds and other undesirable components from the lubri- cating oil.

The spindle oil referred to is an acid treated 55 paraffin distillate having a gravity of about 28.1° A. P. I. Paraffin gas oil having a gravity of about 30.5° A. P. I., pitch still distillate having a gravity of about 37.3° A. P. I. or similar light petroleum oils may also be used. Acid treated

wash oils are recovered from the soap in greater amounts than untreated oils, oils containing polar groups being especially objectionable. "White oil" is even better than spindle oil in obtaining clean separation and large recovery yields from acidified, used green acid soap. In a process of the class hereinabove described it is essential to effect good separation between the green acid soap solution and the light oil phase. 5

10 We have found that, generally speaking, the amount of wash oil which can be separated from the green acid soap decreases with increasing acidity, as will be noted from the general slope of the curves in Figure 2. These curves, however, show an unexpected peak between an acidity of .05 and .10 cc. excess sulfuric acid (92½%) per 100 cc. soap. In other words, at these peaks a maximum oil separation is obtained on the acid side of the curve. 15

15 20 By reference to Figure 3 it will be observed that unless the mixture is acid there will be no appreciable extraction of undesirable constituents. In other words, at an acidity of 0.02 cc. there is four times as much extract in the oil 25 as could be obtained from a neutral or alkaline solution. In view of Figure 3 then, it is evident that the light oil extraction of green acid soap should be in acid solution, and in view of Figure 2 it is seen that the acidity should preferably 30 be slight, that is of the order of .05-.10 cc. excess sulfuric acid (92½%) per 100 cc. of soap solution.

35 Instead of making single extractions to remove impurities from the used green acid soap we may employ countercurrent extractions or a plurality of successive extractions. If successive extractions are employed, equally good results may be obtained by the use of a much smaller 40 quantity of light oil and this must be balanced from an economic standpoint against the added

cost of equipment, manipulation, etc. required for repeated or countercurrent extractions.

5 The particular apparatus employed forms no part of the present invention and it will therefore not be described in detail. The general steps are indicated in the flow sheet of Figure 1 which is self explanatory. The invention relates more particularly to the idea of means for reviving spent green acid soap so that it may be reused in the treating of emulsions or the extraction of mahogany soaps from lubricating oils. 10 An important feature of the invention is the regulation of acidity prior to extraction with light oil.

15 While we have described the invention in detail it should be understood that we do not limit ourselves to the specific conditions hereinabove set forth except as defined by the following claims which should be construed as broadly as the prior art will permit. 20

We claim:

1. In the method of extracting mahogany compounds from green acid compounds with light oils, the step which comprises adjusting the acidity of the mixture to about the equivalent of .05 25 to .10 cc. of 92.5% sulfuric acid per hundred cc. of soap solution and extracting the mixture at this critical acidity with a light oil.

2. The method of reviving spent green acid 30 soap which has been exhausted as a treating reagent for lubricating oils because of contamination with mahogany soap and other impurities, which method comprises acidifying said spent green acid soap to the equivalent of .05 to .10 cc. of 35 92.5% sulfuric acid per hundred cc. of soap solution and extracting the acidified soap with a light hydrocarbon oil whereby the extracting oil may be separated from the extracted material by distillation. 40
